OF D 15,858

DESIGN.

—
J. L. FOLSOM.

CARPET.

No. 15,858.

Patented Feb. 24, 1885.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 15,858, dated February 24, 1885.

Application filed January 14, 1885. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The design consists of four flower and leaf groups and small work in the intervening spaces, with connecting-work resembling twisted strands. The groups are not closely massed,

and consist of small leaves and flowers and of blossom-clusters. The connecting-work of 20 twisted strands irregularly traverses the face of the design, approaching but not interblending with the groups, all as clearly shown in the photograph.

I claim—

1. The design for a carpet, consisting of the flower and leaf groups, substantially as shown and described.
2. The design for a carpet, consisting of the flower and leaf groups and the connecting-work of twisted strands, substantially as shown and described.

J. L. FOLSOM.
